110,019

DESIGN FOR A COMBINED TABLE AND RADIO RECEIVING SET

Daniel J. Crowley, Grosse Pointe, Mich.

Application April 4, 1938, Serial No. 76,284

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Combined Table and Radio Receiving Set, of which the following is a specification, reference being had therein to the accompanying drawing, forming a part thereof, wherein; my new design for a combined table and radio receiving set is illustrated by a perspective view.

The design of combined table and radio receiving set is symmetrical about its vertical axis

in that the side of the set opposite the side shown in the drawing is the same in appearance, with the exception that the opening exposing the graduated dial is omitted.

The dominant feature of my design consists in the portions illustrated in full lines. The member illustrated by the dotted lines at the top of the table represents a tray.

I claim:

The ornamental design for a combined table and radio receiving set substantially as shown and described.

DANIEL J. CROWLEY.
